UNITED STATES PATENT OFFICE.

JOSEPH J. DULLE, OF KANSAS CITY, MISSOURI.

ELEVATOR-GATE-OPERATING APPARATUS.

1,252,331.

Specification of Letters Patent.

Patented Jan. 1, 1918.

Application filed September 20, 1917. Serial No. 192,815.

To all whom it may concern:

Be it known that I, JOSEPH J. DULLE, a citizen of the United States, and resident of Kansas City, in the county of Jackson and 5 State of Missouri, have invented certain new and useful Improvements in Elevator-Gate-Operating Apparatus, of which the following is a specification.

This invention relates to electric elevator 10 gate operating apparatus, and has for its objects to provide means whereby the elevator operator on stopping the car at any landing, must complete an electric circuit to effect the opening of the gate for such 15 landing, means for opening the gate and incidentally breaking the car operating circuit to render further travel of the car impossible, and means whereby the operator may reestablish the first-named circuit through 20 branch conductors for effecting the reclosing of the gate and the return of certain connections of the car operating circuit to normal position so that travel of the car may be resumed.

25 A further object is to provide emergency manually-operable means for completing the car operating circuit through branch conductors in the event it is necessary or desirable to operate the car when one of the 30 gates is open.

Another object is to provide means for preventing a gate from being opened from a landing with the aid of the counter-balance weight thereof.

35 With these objects in view the invention consists in certain novel and peculiar features of construction and organization of parts as hereinafter described and claimed; and in order that the invention may be fully 40 understood, reference is to be had to the accompanying drawings, in which:

Figure 1, is a diagrammatic view of electrical circuits and connections embodying my invention.

45 Fig. 2, is a fragmentary vertical section through the elevator hatch way of a building equipped with my invention.

Fig. 3, is a horizontal section on the line III—III of Fig. 1. Fig. 4, is a section on 50 line IV—IV of Fig. 3.

Referring now to the drawings, in which like reference characters identify corresponding parts in all of the figures, 1 and 2 represent the positive and negative feed wires from any suitable source of electric current supply.

55 Located in a building at any suitable

point is a switchboard SB, for the flow of current over a wire 3 from the feed wire 1 and for the flow of current over a wire 4 60 to the feed wire 2. Arranged preferably at the top of the elevator shaft is an electric motor 5, for operating a hoisting drum, not shown, for raising and lowering the car, said motor being connected in circuit with wires 65 1 and 2 through the switchboard in any suitable or conventional manner, 7 and 8 indicating wires in circuit with the switchboard and motor.

From the switchboard, a wire 9 leads to 70 the lever 10 of the controller 11 on the elevator car 12. From the controller, the wires 13 and 14 connect with a wire 15 leading to a pole 16, of one of a series of switches 17, for each landing in the building. The 75 other pole 18 of the switch is connected by a wire 19 to the pole 16 of the switch for the next landing, the pole 18 of said switch is connected by a wire 20 to the pole 16 of the remaining switch, and the pole 18 of 80 the latter is connected by a wire 21 to one pole 22 of an emergency switch. The lever 23 of said switch is normally held out of engagement with said pole by a spring 24, so that the current must ordinarily flow 85 through all of the switches 17, which are connected in series, it being obvious that if the circuit is broken through one of said switches 17, it will be impossible for the motor 5 to be operated. It will be understood that whether the current flows through 90 switches 17 to pole 22, or through the switch lever 23, it must pass back to the switchboard through the connection 25, and it will be noted in this connection that when the 95 emergency switch is closed, it is necessary that pressure on lever 23 shall be maintained during the travel of the car, as the instant the pressure is removed from said lever, the circuit will be broken and the car arrested. 100

The controller 11, is mounted as usual upon the car, though not so shown herein, and also mounted upon the car is an electric magnet 26, in the car operating circuit.

The magnet 26 is secured rigidly upon 105 the car adjacent to a motor 27 provided with a foot or base 28 slidingly mounted in a guide bracket 29, one or more push springs 30 being employed to slide the motor away from the magnet 26 when the latter is de-energized. When said magnet is energized, it overcomes the resistance of said spring or springs and attracts the motor.

The shaft of the motor is equipped with

a gear pinion 31 meshing with a gear wheel 32 the shaft of which is journaled in bearing arms 33 projecting from the base of the motor, said gear wheel carrying a small gear 32^a. When the motor is attracted by and slides toward the magnet, the large gear wheel 32 and gear 32^a are carried with it to position the latter out of the vertical plane of certain rack-bars hereinafter more 10 particularly referred to.

Extending vertically through the shaft at one side of the car, is a pair of channel bars 34, which conjointly constitute a guideway upon which are secured the switches 17, 15 and said switches comprise in addition to the poles 16 and 18, the bars 36 for normally electrically connecting the said poles. Each bar 36 carries a pair of rods 37 having collars 38 or the like, and springs 39 bearing 20 at their opposite ends against the connecting bars 36 and cross bars 40 secured upon a pair of suitable guide push rods 41, and mounted upon the push rods and bearing against the casing 42 and bars 40 of the 25 switches, are springs 43, which springs when unopposed, effect the disengagement of connecting bars 36 with the poles 16 and 18, as hereinafter appears. Normally, that is when the gates are closed, the rods 41 are 30 held in advanced position, and through bars 40 and spring 39, hold the connecting bars 36, yieldingly against said poles 16 and 18.

For each landing there is a slidable 35 weight 44 mounted in a well-known manner as shown, for travel in said guideway below the respective switch 17, and said switches are closed when said weights are elevated, the upper ends of the weights advancing the rods 41 by applying pressure thereon. Each weight, which may be of any suitable character, is equipped with a vertical rack bar 45 for engagement by the small gear 32^a, when the car is stopped at 40 the respective landing and the magnet 26 is deenergized, as hereinafter appears. Ordinarily the said gear 32^a is free to pass without engagement with the rack bars.

When the car is stopped at a landing by 45 disposing the controlling lever in neutral position as customary, the magnet is deenergized and the motor is moved away from the magnet by spring or springs 30, until the said gear 32^a engages the rack bar, in which position the gear must remain until the car operating circuit is again reestablished, and when reestablished reenergizes the magnet and withdraws the said gear from engagement with the rack bar.

60 After the gear has automatically engaged the rack bar as explained, it is necessary to complete a circuit to operate the motor 27, in a certain direction for the purpose of lowering the weight and thereby opening the 65 gate 46, of the respective landing, and to

accomplish this certain electrical connections and devices are provided.

The landing gates 46 are shown as of the single type for vertical movement, but of course may be of the double type or of any 70 special type of construction, and connecting the upper part of each gate with the respective weight, is a cable 47 extending over suitable guide sheaves 48, so arranged that the cable shall not extend across the path 75 of the elevator car.

To prevent the gates being opened from the landings with the aid of the counter-balancing force of the respective weights, hook-shaped catches 48^a are pivoted to the 80 guideway at the landings, springs 48^b secured to the guideway, pressing against the catches to hold the hooks thereof yieldingly below the rack-bars. When the motor 27 is moved, following the stoppage of the car 85 and deenergization of the magnet, the shaft of the gear wheels 32 and 32^a applies sufficient pressure on the respective catch above the pivotal point thereof to effect the withdrawal of the hook of the catch from under 90 the respective weight, as shown by full lines. Fig. 2, this being accomplished, before or by the time the gear 32^a engages the rack bar and imparts downward movement there-to to open the gate. After the car moves 95 either up or down sufficiently to disengage the shaft of said wheels from the catch, the spring 48^b snaps the hook of the catch against the toothed edge of the rack bar, where it remains until the weight is fully re-elevated, the hook being wide enough to 100 avoid catching between the rack teeth, it being understood that the rack bar in length exceeds its extent of travel so that the dog can never overlie it and interfere with re-closing movement of the gate.

Referring now to the electric connections for the operation of the motor 27, 49 is a wire leading from feed wire 1 to the customary box B, usually located half way up the elevator shaft, and from said box said wire leads to said motor 27. Arranged in the shaft near each landing and accessible to the car operator when the car stops at the respective landing, are hand switches, 110 comprising levers 50 electrically connected by wire 51 to said wire 2, and poles 52 and 53, the levers being engaged with poles 52 when the weights are elevated and the gates are closed. Poles 52 are connected by 115 wires 54 to the upper switch levers 55, and springs 56 when unopposed cause said levers to engage switch poles 57 electrically connected by wire 58 through the box B to the motor 27.

120 Poles 53 of the hand switches, are connected by wires 59 to the lower switch levers 60 normally held in electric engagement by spring 61 with switch poles 62 electrically connected by wire 63 through the box 125 130

B with said motor 27. With the hand switches positioned as shown, the circuit is broken through the motor 27 from wire 63, and is broken from wire 58 because the 5 switch levers 55 are disengaged from the poles 57.

For the purpose of operating the levers 55 and 60, said levers are provided with 10 arms 64 equipped with rollers 65, and each weight is equipped with a cam bar 66 of such length that when the respective weights are elevated, said cam bars are above the levers 60 leaving the spring 61 free to close said levers against poles 62 as shown. At 15 such time the cam bars are in engagement with the rollers of levers 55 and are holding said levers withdrawn from the poles 57. Now when the car stops at a landing, the topmost landing for example, and all gates 20 are closed, a circuit for operating motor 27 may be established by throwing the lever 50 of the uppermost hand switch, from engagement with the pole 52 and into engagement with the pole 53, the circuit established being as follows: from wire 1 through wire 49, box B, motor 27, wire 63, pole 62 of the lower hatch way or shaft switch for the topmost landing, thence through switch lever 60, wire 59, pole 53, lever 50, and wire 30 51 to feed wire 2. The establishment of this circuit operates the motor and through the geared relation between the same and the rack bar of the respective landing, the corresponding weight is lowered and the gate 35 connected thereto is raised or opened, it being noted that as the lowering of the weight begins, the springs 43 of the respective switch 17, withdraw the connecting bar 36 from engagement with the poles 16 and 18 40 and thus break the car operating circuit, this circuit remaining open until the gate is closed, unless the emergency switch is operated. To close the gate, the car operator must return switch lever 50 to its original 45 position, it being understood that when the weight was lowered in the opening of the gate, the cam bar released the uppermost of the pair of hatchway or shaft switches of the respective landing, to permit the switch 50 lever 55 to close and then open the circuit through the cam bar engaging and operating the other switch lever 60 of said pair of switches. As the switch lever 50 is thus returned to its initial position, circuit is 55 completed through the motor for reverse operation of the same to re-elevate the weight and reclose the gate, this circuit being as follows: from feed wire 1 through wire 49, box B, motor 27, wire 58, pole 57, lever 55, wire 54, pole 52 of the hand switch, lever 50 of said switch, and wire 51 to feed wire 2, and the re-elevation of the weight effects upward movement of the push bars 41 and the yielding pressure of bar 36 against poles 16 60 and 18 of the respective switch 17, and

thereby enables the operator by throwing the controller lever, to recomplete the circuit through motor 5 and effect travel of the car.

In the event that a gate is left open and 70 it is inconvenient for the operator to close it or to send some one to do so, he can close the circuit through the motor 5 by pressure on switch lever 23, and thereby complete a circuit as follows: from feed wire 1 through 75 wire 3, switch board, wire 8, motor 5, wire 7, back to switch board, thence through wire 9 to lever 10 of the controller 11, and from the controller through wire 13 or 14 according to the direction in which it is desired the car shall move, to wire 15, then through the lever 23, contact 22, and wire 25 back to the switch board, and from the latter through wire 4 to feed wire 2, it being noted in this connection, that current through the 80 emergency switch will cease flowing the instant pressure on the lever 23 is removed, it being desirable to put the operator to some trouble in order to close the circuit through the emergency switch to discourage use 85 thereof except in emergencies. The completion of this circuit of course energizes the magnet to cause the same to attract and draw the motor 27 and gearing to inoperative position with respect to the rack bars. To 90 arrest and support the counter-balance weights when released by the gear 32, stop bars 67 are secured to the guideway at proper intervals.

From the above description it will be 100 apparent that I have produced apparatus for increasing the safety of operation of elevator cars, and while it is shown and described as for use with freight elevators, it is to be understood that it is susceptible 105 for use with passenger elevators, and it will also be apparent that various changes in the detail construction, form and arrangement of the parts may be made without departing from the spirit and scope of the 110 appended claims.

I claim:

1. The combination in a structure having an elevator car, gates controlling the landings for the car and counter-balance weights 115 for the gates, of holding means for each weight to prevent downward movement thereof when the respective gate is closed, means for tripping either of said holding means to free the respective counter-balance weight for downward movement, an electric motor carried by the car, means to throw said motor into operative relation to the weight of any landing at which the car stops, and means for operating the motor 120 to effect downward movement of such weight.

2. The combination in a building having an elevator car, gates controlling the landings for the car and counterbalance weights 130

- for the gates, of holding means for each weight to prevent downward movement thereof when the respective gate is closed, means for tripping either of said holding 5 means to free the respective counter-balance weight for downward movement, a motor upon the car, means to place the motor in operative relation with the weight to impart movement to the same after the holding 10 means has been tripped, means for circulating an electric current through the motor to effect the lowering of the weight, and means for reversing the flow of the current to reverse the operation of the motor to 15 effect the re-elevation of the weight.
3. The combination in a building having an elevator car, gates controlling the landings for the car and counterbalance weights for the gates, of holding means for each 20 weight to prevent downward movement thereof when the respective gate is closed, means for tripping either of said holding means to free the respective counter-balance weight for downward movement, a motor 25 upon the car, means to place the motor in operative relation with the weight to impart movement to the same after the holding means has been tripped, means for circulating an electric current through the motor to 30 effect the lowering of the gate, means for reversing the flow of the current to reverse the operation of the motor to effect the re-elevation of the weight, and means for restoring the motor to inoperative position 35 with relation to the weight.
4. The combination in a building having an elevator car, gates controlling the landings for the car and counterbalance weights for the gates, of holding means for each 40 weight to prevent downward movement thereof when the respective gate is closed, means for tripping either of said holding means to free the respective counter-balance weight for downward movement, a motor 45 upon the car, means to place the motor in operative relation with the weight to impart movement to the same after the holding means has been tripped, means for circulating an electric current through the motor to 50 effect the lowering of the weight, means for reversing the flow of the current to reverse the operation of the motor to effect the re-elevation of the weight, and an electro-magnet for withdrawing the motor from 55 operative relation to said weight.
5. The combination in a structure having an elevator car, gates controlling the landings for the car and counterbalance weights for the gates, of a motor on the car, means 60 for placing the motor in operative relation

to the weight for any gate when the car is at the respective landing, and means for operating the motor to effect movement of the weight in the desired direction.

6. The combination in a structure having 65 an elevator car, gates controlling the landings for the car and counterbalance weights for the gates, of a motor on the car, means for placing the motor in operative relation to the weight for any gate when the car is 70 at the respective landing, means for operating the motor to effect movement of the weight in the desired direction, and means to restore the motor to inoperative position when the weight is elevated. 75

7. The combination in a structure having an elevator car, gates controlling the landings for the car and counterbalance weights for the gates, of a motor on the car, means for placing the motor in operative relation 80 to the weight for any gate when the car is at the respective landing, means for operating the motor to effect movement of the weight in the desired direction, means to restore the motor to inoperative position when 85 the weight is elevated, and automatic means for preventing downward movement of the weight when the motor occupies its inoperative position.

8. In a structure having an elevator car, 90 gates controlling the landings for the car and counter-balance weights for the gates, the combination of electrical devices including a motor for operating the car, a controller on the car, an electro-magnet and a 95 circuit breaking switch for each landing, the circuit breaking switches being connected in series with the motor, controller and magnet, and held closed by said weights when the gates are closed, a motor on the car for 100 attraction to inoperative position by the magnet when the latter is energized, means for disposing the motor in operative relation to the respective weight when the car is stopped at a landing by breaking the circuit through the magnet and first-named motor by operation of the controller, a pair of automatically closing switches electrically connected to the motor on the car and adapted to be alternately opened and released by the weight in moving from one position to another to effect movement of the gate, and a hand switch for completing a circuit through the closed automatic switch to operate the motor to effect travel of the 110 weight until it releases the opened automatic switch and opens the closed automatic switch. 115

In testimony whereof, I affix my signature.
JOSEPH J. DULLE.
